US0D1024940S

(12) **United States Design Patent** (10) **Patent No.:** **US D1,024,940 S**
(45) **Date of Patent:** **** Apr. 30, 2024**

(54) **DEVICE WITH HOLDER**

(71) Applicant: **Amazon Technologies, Inc.**, Seattle, WA (US)

(72) Inventors: **Jesse Wheeler Moore**, Oakland, CA (US); **Giles David Matthew McWilliam**, San Francisco, CA (US)

(73) Assignee: **AMAZON TECHNOLOGIES, INC.**, Seattle, WA (US)

(**) Term: **15 Years**

(21) Appl. No.: **29/783,730**

(22) Filed: **May 14, 2021**

(51) LOC (14) Cl. **14-03**

(52) U.S. Cl.

USPC **D14/253**; D13/108

(58) **Field of Classification Search**

USPC D13/103, 107, 108, 109, 110, 118, 119; D14/251, 252, 253, 432, 434; D12/415, D12/422, 425

CPC H02J 7/0044; H02J 7/0045; H04B 1/3877

(57) **CLAIM**

The ornamental design for a device with holder, as shown and described.

DESCRIPTION

FIG. 1 is a top, front, right-side perspective view of a device with holder;

FIG. 2 is a top, back, right-side perspective view thereof;

FIG. 3 is a bottom, back, left-side perspective view thereof;

FIG. 4 is a bottom, front, right-side perspective view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The dashed broken lines depict portions of the device with holder that form no part of the claimed design.

1 Claim, 10 Drawing Sheets
